(57) **CLAIM**

The ornamental design for a physiological monitor having a removable module, as shown and described.

DESCRIPTION

FIG. 1 is a front view of a physiological monitor having a removable module shown with the removable module installed showing our new design;

FIG. 2 is a side view thereof;

FIG. 3 is a bottom view thereof;

FIG. 4 is a perspective view thereof; and,

FIG. 5 is an exploded perspective view of the physiological monitor having a removable module shown with the removable module removed.

It will be understood that the broken lines are included for the purpose of illustrating unclaimed portions of the physiological monitor having a removable module and form no part of the claimed design.
